Primary Examiner—Terry A Wallace(74) *Attorney, Agent, or Firm*—Walter A. Hackler(57) **CLAIM**

The ornamental design for a bakery cutting guide, as shown and described.

DESCRIPTION

FIG. 1 is a perspective view of a bakery cutting guide showing a top of my new design shown, front and end view;

FIG. 2 is a side elevated view of the present invention, both sides of the bakery cutting guide being identical; and,

FIG. 3 is an end elevated view of the present invention both ends of the bakery cutting guide being identical.

No distinguishing features of the bakery cutting guide are present on a bottom of the bakery cutting guide.

1 Claim, 1 Drawing SheetFIG. 1.

FIG. 2.

FIG. 3.
